UNITED STATES PATENT OFFICE.

HENRY A. DOLGE, OF DOLGEVILLE, NEW YORK.

DESIGN FOR A BICYCLE-RACK.

SPECIFICATION forming part of Design No. 26,765, dated March 16, 1897.

Application filed January 25, 1897. Serial No. 620,699. Term of patent 33 years.

To all whom it may concern:

Be it known that I, HENRY A. DOLGE, residing at Dolgeville, in the county of Herkimer and State of New York, have invented and produced a new and original Design for Bicycle-Racks, of which the following is a specification, reference being had to the accompanying drawing, in which the figure represents a perspective view of my design.

The leading feature of my design consists in the ornamental representation of the base members, which have a straight central top portion 1 and the ogee top curved portions 2, which terminate at the ends in laterally-projecting shoe-like members 3, which lie below the plane of the body of the base members to produce a cut-out or recess ornamentation 9.

The design also embodies the transverse parallel members 5, which extend from one

base member to the other, a central transverse portion 4, which sets back under the members 5, the edges of which overlap such portion. From the ends of the members 5 extend vertically flat bars 6, which merge at the upper end in the transverse lintel or molding 7, on the top of which is an ornamental head member 8. The members 5 and 7 are also joined by a series of rungs 10, the lower ends of which appear as extending down between the said members 5.

What I claim is—

The design for a bicycle-rack, substantially as shown and hereinbefore described.

HENRY A. DOLGE.
